UNITED STATES PATENT OFFICE

ALBERT C. MEYER, OF GLENSHAW, PENNSYLVANIA

DESIGN FOR A BOTTLE

Application filed July 21, 1931. Serial No. 40,612. Term of patent 14 years.

To all whom it may concern:

Be it known that I, ALBERT C. MEYER, a citizen of the United States, residing at Charles Street, Glenshaw, county of Allegheny and State of Pennsylvania, have invented a new, original, and ornamental Design for Bottles, of which the following is a specification, reference being had to the accompanying drawings, forming part thereof, in which:

I claim:

The ornamental design for a bottle, as shown.

ALBERT C. MEYER.
